ELEVATOR DISPATCHING SYSTEM

William F. Eames, Pittsburgh, Pa., assignor to
Westinghouse Electric Elevator Company, Chi-
cago, Ill., a corporation of Illinois

Application September 13, 1935, Serial No. 40,387

32 Claims. (Cl. 177—336)

My invention relates to elevator dispatching systems and more particularly to elevator dispatching systems of the non-rotational type.

One object of my invention is to provide an elevator dispatching system which may be easily and economically constructed, installed, operated and maintained in operation.

Another object is to reduce the number of signal devices and the amount of wiring usually employed in dispatching systems.

A further object is to produce a dispatching system which will automatically adjust itself to the amount of traffic the elevator system is handling.

15 A further object is to provide independent and automatic adjustment of the interval at which the dispatching signals are given in accordance with slowly increasing down traffic and slowly decreasing up traffic or vice versa.

20 A still further object is to provide a dispatching system which will require no manual adjustment of the dispatch-giving means at the top terminal with respect to the operation of the dispatching signals at the bottom terminal.

25 It is also an object of my invention to provide a dispatching mechanism which will operate independently of the arrival of the cars at the terminals and without the necessity of providing selector segments and terminal limit switches for operating the system.

30 For a better understanding of the invention, reference may be had to the accompanying drawings in which:

35 Figure 1 is a diagrammatic representation of an elevator system embodying my improved dispatching system.

Fig. 2 is a top plan view of the dispatching timer embodied in the improved system shown in Fig. 1.

40 Fig. 3 is a view, in end elevation, of a disc and switches operated by the timer shown in Fig. 2 for the purpose of sequentially opening and closing certain circuits in the dispatching system.

45 Fig. 4 is a view, in end elevation, of a disc and switch operated by the timer shown in Fig. 2 for controlling a dispatching circuit at one of the terminals.

50 Fig. 5 is a "straight line" drawing of the circuits for the dispatching apparatus shown in Figs. 1 to 4, and

55 Fig. 5A is a diagrammatic representation of the relays and associated contact members embodied in Fig. 5.

The illustration of the relays in Fig. 5A shows them with their coils and contact members disposed in horizontal alinement with their positions in the circuits represented in Fig. 5 so that the reader may readily determine the identification of any relay, the number and kind of its contact members and the position of its coils and

contact members in the "straight line" circuits. In considering the diagram shown in Fig. 5, the drawing comprising Fig. 5A should be placed at either the left hand side or the right hand side of the sheet of drawing bearing Fig. 5.

5 For convenient reference the main relays and parts are indicated in the drawings by the following reference letters.

T=	Dispatching timer, contact members	10
TT	for top, BT for bottom.	
K=	Sequence device.	
C=	Car signal lamp, one in each car.	
L=	Lower terminal floor lantern lamps, one for each car.	
W=	Up direction preference relays, one for each car.	15
X=	Down direction preference relays, one for each car.	
U=	Up direction preparing buttons, one for each car.	20
D=	Down direction preparing buttons, one for each car.	
M=	Dispatch preparing relays, one for each car.	
N=	Car selecting relays, one for each car.	25
TS=	Top signal storing relay, common to all cars.	
TSA=	Top signal delay relay, common to all cars.	30
BS=	Bottom signal storing relay, common to all cars.	
E=	Top start signal relay, one for each car.	
F=	Bottom start signal relay, one for each car.	35
G=	Signal cancelling switch, one for each car.	

Referring more particularly to the drawings, in Fig. 1, I have illustrated an elevator installation comprising four cars designated as 1, 2, 3 and 4, serving five floors. Although I have shown four cars, the system may be applied to any desired number of cars serving any desired number of floors.

45 Each car is provided at the lower terminal with a floor lantern which may be operated to indicate to intending passengers when that car is to be the next car to leave so that the passengers may move to and enter the next car to make an up trip. These floor lanterns may be of any suitable design and are indicated in the present instance as lamp 1L for car 1, lamp 2L for car 2, lamp 3L for car 3 and lamp 4L for car 4.

55 A suitable signal device such as an electric lamp is mounted in each car for the purpose of giving a "next" signal to the attendant of that car when it is to be the next to receive a dispatching signal. The car signal lamps are designated as 1C for car 1, 2C for car 2, 3C for car 3 and 4C for car 4.

60

In order to reduce the number of signal devices and the amount of wiring in the cars in connection with my dispatching system, I provide for giving the attendant in each car his start signal by causing his "next" lamp to flicker or flash when he is being given his dispatching signal. By causing the car lamps to flicker after burning steadily during the operation of the warning "next" signal, I have eliminated the necessity of providing a separate starting lamp and the wiring which would be necessary for its operation.

In Fig. 2 I have disclosed a special timing device T for operating the dispatching system. The timing device comprises a timing motor 10 disposed on a bed plate 11 for operating a shaft 12 leading to a gear speed reducing device 13. The speed reducing device 13 rotates a shaft 14 on the other end of which is disposed a gear pinion 15 in position to mesh with a beveled gear 16 for rotating a timing shaft 17. The right hand end of the shaft 17 is connected to an electromagnetic clutch 20 comprising a pair of co-operating clutch plates 21 and 21a. The clutch plate 21a is mounted on the inner end of a shaft 22 disposed in a suitable bearing 23 and having on its outer end a disk 24. The disk 24 (Fig. 4) may be held in position on the shaft 22 by means of a set screw 25.

The shaft 22 is disposed to be movable longitudinally in the bearing 23 and a spring clip 26 is disposed between the bearing and the disk to normally bias the shaft and the clutch plate 21a away from the clutch plate 21. A winding 28 is disposed around the base 29 of the clutch plate 21. When the winding 28 is energized, the clutch plates 21 and 21a become magnetized and are drawn together with sufficient force to overcome the biasing effect of the spring 26 and thereby cause the disk 24 to rotate with the timing shaft 17. The disk 24 (Fig. 4) is provided with a cam surface 30 disposed to operate a timing switch 31.

A similar clutch 33 comprising a pair of electromagnetically operated clutch plates 34 and 34a are disposed on the left-hand end of the shaft 17 for operating a switch member 32. The switch member 31 is biased by a spring 31a to normally close its contact members BT2. A spring 32a biases the switch member 32 to normally close its contact members TT2. When the clutches are energized, the cam 30 operates to temporarily open the contact members BT2 and close BT1 and the cam 78 operates to temporarily open the contact members TT2 and close TT1 once for each revolution of the shaft 17.

As shown in Fig. 5, the timing motor is provided with an armature 35 and a shunt field winding 36, with which are associated the resistor R5, the effective length of which may be changed by a movable connector 37 to adjust the speed of the timing motor. In usual practice, the motor will be designed to rotate the timer shaft once within a range of from twenty to forty seconds. In the present case, it will be assumed that the motor is adjusted to rotate the timer shaft 17 once every thirty seconds.

In practicing my invention, I also provide a sequence device K comprising a disk 40 fixed upon the shaft 14 to rotate therewith. The disk 40 may be secured to the shaft 14 by a suitable set screw 41. A cam surface 42 is disposed on the outer edge of the disk to engage and operate a plurality of switches, one for each car. The switch for car 1 is designated as 1K, that for car 2 as 2K, that for car 3 as 3K and that for car

4 as 4K. The sequence device is constructed to operate its switches at more frequent intervals than the timer switches, and it should be so proportioned that disk 40 will rotate with sufficient speed to operate one of its switches every second so that the sequence switch for each car will be closed temporarily every four seconds. The sequence switches are disposed in certain circuits, as will be later described, to cooperate with certain relays in selecting the next car to receive the next dispatching signal.

In my system, each attendant upon arriving at a dispatching terminal, presses a direction preparing button for conditioning his car to receive its dispatching signal at the proper time. The circuit may be operated automatically by the arrival of the car at the terminal closing a limit switch but I prefer the manual operation of preparing buttons by the attendants. The up direction preparing buttons are designated as 1U in car A, 2U in car B, 3U in car 3, and 4U in car B. The down direction preference button in car 1 is designated as 1D, in car 2 as 2D, in car 3 as 3D, and in car 4 as 4D.

A plurality of dispatch preparing relays M are disposed to be operated by the direction preparing buttons to hold the car in preparation for receiving the dispatching signal after the corresponding direction preparing button has been pressed. The dispatch preparing relay for car 1 is designated as 1M, that for car 2 as 2M, that for car 3 as 3M and that for car 4 as 4M. Each of these relays, upon being energized, locks itself in and remains energized until it is restored as will be hereinafter described.

A plurality of up direction preference devices such as relays or switches W and a plurality of down direction preference devices such as relays or switches X are provided for cooperation with the dispatch preparing relays M in preparing the cars for receiving the dispatching signals. The up direction preference relay for car 1 is designated as 1W, that for car 2 as 2W, that for car 3 as 3W and that for car 4 as 4W. The down direction relay for car 1 is designated as 1X, that for car 2 as 2X, that for car 3 as 3X and that for car 4 as 4X.

The direction preference relays may be operated by any suitable means which will cause them to operate in accordance with the direction in which the car is operating. If desired, they may be operated by suitable limit switches as shown in the Patent No. 2,042,201, issued May 26, 1936, Signal systems for elevators, by Harold W. Williams and William F. Eames or, they may be operated by frictional direction reversing switches driven by the floor selector, which is old and well known in the signal art.

A plurality of car selecting relays N are provided for operation, in response to the cooperative operation of the sequence device K, the preparing buttons and the preference relays. The operation of the car selecting relays N is controlled by a pair of selective resistors R3 and R6 in such manner that only one car selecting relay can be energized at one time. When one of the car selecting relays is energized for the up direction, the resistance R3, being in circuit with the coil of that relay, will prevent the flow of sufficient current through the coil of any other car selecting relay to energize such other car selecting relay. When a car selecting relay is energized for the down direction, the selective resistance R6 will prevent the flow of sufficient current through the coil of any other car selecting relay in the

down direction to energize that other relay. Hence, it will be seen that only one car selecting relay can be energized at any one time at the bottom terminal and only one car selecting relay 5 can be energized at any one time for the top terminal. The car selecting relay for car 1 is designated as 1N, that for car 2 as 2N, that for car 3 as 3N and that for car 4 as 4N.

At times it will happen that no car will be at 10 a dispatching floor to receive the dispatching signal given by the timing mechanism for that floor. Therefore, I have provided a top signal storing relay TS for the upper terminal and a bottom signal storing relay BS for the lower 15 terminal. These storing relays are common to all the cars and operate to store a dispatching signal at a terminal until a car is ready to receive it at that terminal.

A top "start" signal relay E and a bottom "start" signal relay F are provided for each car. 20 These relays effect the lighting of the signal lamps in the next car to leave and effect the connection of the timing switch to the motor to subsequently flicker the signal lamp for giving 25 the start signal. The top start signal relays for the upper terminal are designated as 1E for car 1, 2E for car 2, 3E for car 3 and 4E for car 4. The "start" signal relays for the bottom terminal are designated as 1F for car 1, 2F for car 2, 3F for 30 car 3 and 4F for car 4. The starting relays F respond to the cooperative action of the timing switches BT2, the bottom storing relay BS, the car selecting relays N and the direction preference relays W. The starting signal relays F 35 respond to the cooperative action of the timing switch contact members TT2, the top storing relay TS, the car selecting relays and the direction preference relays X. When a starting relay is energized, it provides a self-holding circuit for 40 itself and it will remain energized and maintain its corresponding starting signal in operation until its corresponding car acts to leave the dispatching floor.

In order to cancel the dispatching signals and 45 restore the starting signal relays when the cars act upon the dispatching signal, I have provided for so connecting the starting relay for each car to its door mechanism (not shown) or its starting switch (not shown) that the action by the 50 attendant in obeying the starting signal will cause the cancellation of the starting signal and the restoration of the corresponding starting relay. The cancellation means comprises a plurality of 55 switches or relays G, that for car 1 being designated as 1G, that for car 2 as 2G, that for car 3 as 3G and that for car 4 as 4G. Inasmuch as these switches may be connected for operation by any part of the starting mechanism of the departing cars, in any well known manner, no specific details have been given and they are 60 simply marked with their designating character.

In practicing my invention I also provide a 65 novel means for automatically adjusting the time of giving the top terminal dispatching signal with reference to the time of giving the bottom terminal dispatching signal. This means comprises a top signal delay relay TSA common to all the cars. The relay TSA is designed to delay the closing of its normally closed contact members 70 TSA1 when it is deenergized after being energized. This is more fully explained later. The time delay relay TSA is normally energized to hold its contact members in open position and 75 is so controlled by the top storing relay TS as

to be deenergized only when the top storing relay TS is energized.

The means for causing an operated "next" or "start" lamp C to flicker for the giving of the dispatching or starting signal comprises a flicker device 45 labeled with the word "flicker" in Fig. 5. The flicker device may be any well known flicker or flashing button, for instance, such as is often used in connection with Christmas tree lights and in advertising devices or other novelty systems. 10 It is found that the operation of a flickering light is an even more catching and attention compelling signal than a steady lamp or a lamp of a different color.

At times, the dispatcher attendant at the 15 lower terminal may desire to cause a car to leave a dispatching terminal immediately instead of waiting for the giving of the next dispatching signal. I have provided for this operation by locating a bottom starting button 46 and a top 20 starting button 47 at the lower terminal. These buttons are disposed in the circuits for the "start" signal relays and in order to prevent the circuits from giving the start signal for more than one up car or more than one down car at a time, the 25 circuits for the bottom starting relays F are connected through a selective resistance R2 and the circuits for the top start signal relays E are connected through a selective resistance R4. By reason of these selective resistances, only one 30 starting relay at each terminal may be operated at one time by the dispatcher's buttons 46 and 47.

The invention may be understood best by an assumed operation of the apparatus shown in the drawings.

It will be assumed that the line switches 55 are closed to connect the dispatching system to a source of electrical energy and that the cars 1, 2, 3 and 4 operating between the terminals, no car being at either the upper dispatching floor 40 or the lower dispatching floor. Under these conditions, the clutches 20 and 33 will be energized because, with no car having operated its button at either dispatching floor, each of the start signal relays E and F will be in a deenergized condition, and their normally closed contact members will be effective to complete a circuit extending from the supply conductor L+, through conductor 58, the contact members TS4, the coil of clutch 33 and contact members 1E4, 2E4, 3E4 50 and 4E4 to the supply conductor L- for energizing the clutch 33, and to complete a circuit from supply conductor L+ through conductors 58 and 59, the coil of clutch 20 and the contact members 1F4, 2F4, 3F4 and 4F4 to the supply 55 conductor L- for energizing the clutch 20.

Inasmuch as the clutch 20 is energized, its clutch plate 21 magnetically attracts the clutch plate 21a, thereby overcoming the effect of the biasing spring 26 and causing the switch disc 24 60 to be rotated by the timing motor 10. The rotation of the disc 24 will, in time, cause its cam 30 to move into such position that it will operate the switch arm 31 to open the contact members BT2 and close the contact members BT1, as will 65 be hereinafter described.

The closing of the switches 55 also energizes the time delay relay TSA by a circuit extending from the supply conductor L+ through conductor 60, the contact members TS2, the coil of relay TSA, and conductor 61 to the supply conductor L-.

The closing of the switches 55 also energizes the timing motor 10 for continuous operation by a circuit extending from the supply conductor 75

L_+ through conductors 58 and 63 to a junction point 64, where the circuit divides, one branch extending through the field winding 36 and the conductor 65 to the supply conductor L_- , and 5 the other branch extending through the rheostat arm 37, resistor R5, armature 35 and conductor 65 to the supply conductor L_- . The timing motor is now energized and conditioned for 10 continuous operation at a substantially constant speed, so that whenever the clutches 20 and 33 are energized, the timing discs 24 and 66 will rotate with the timing motor and operate the timing switches at regular intervals of time.

It will be assumed also that car 1 is approaching and arrives at the lower terminal. Inasmuch as car 1 is concluding a down trip, its down direction preference relay 1X is energized. However, as the car comes into and stops at the lower terminal the down relay 1X is automatically deenergized and the up direction relay 1W for car 1 is accordingly energized for the up direction operation of the car. The energized relay 1W closes its contact members 1W1, 1W2 and 1W3, thereby preparing the circuits for the 20 starting signal relay 1F, the car selecting relay 1N and the floor lantern 1L for operation under certain conditions.

It will be further assumed that the attendant on car 1, after arriving at the lower terminal, 30 presses the up direction preparing button 1U to prepare his car for up direction operation and to connect it to the dispatching system. The pressing of the button 1U energizes the dispatching-preparing relay 1M of car 1 by a circuit extending from the supply conductor L_+ through the coil 1M, the contact members 1F3 and 1E2, and the contact members of button 1U, and conductor 61 to the supply conductor L_- . The energized relay 1M closes its contact members 1M1 and 40 1M2. The closed contact members 1M1 complete a holding circuit for the relay 1M and the closed contact members 1M2 cooperate with the closed contact members 1W2 to prepare the circuit for energizing the car selecting relay 1N of car 1. 45 Inasmuch as no other car is at the lower terminal, sufficient current may be drawn through the selective resistor R3 to energize the relay 1N as its circuit is completed. It will be recalled that the sequence device K is being operated by 50 the timing motor T to rapidly open and close its sequence switches 1K, 2K, 3K and 4K. Consequently, the contact members 1K are soon closed temporarily and this energizes the relay 1N by a circuit extending from supply conductor L_+ , 55 through the resistor R3, the contact members 1W2, the coil 1N, the contact members 1M2 and 1K, and conductor 61 to the supply conductor L_- . The energized relay 1N closes its contact members 1N1, 1N2, 1N3, 1N4 and 1N5.

60 The closing of the contact members 1N3 provides a self-holding circuit for the relay 1N so that this relay now remains energized even though the sequence switch 1K is opened immediately. The closing of the contact members 1N1 65 additionally prepares the circuit of the starting signal relay 1F for operation. The closing of the contact members 1N2 prepares the starting signal relay 1E for operation.

The closing of the contact members 1N4 of the 70 relay 1N energizes the signal lamp 1C in the car by a circuit extending from the supply conductor L_+ , through conductor 68, lamp 1C, and the contact members 1N4, and conductor 61 to the supply conductor L_- . The energized lamp 1C lights to 75 notify the operator that his car will be the next

car to receive the dispatching or starting signal.

The closing of the contact members 1N5 energizes the floor lantern 1L for car 1 at the lower terminal by a circuit extending from the supply conductor L_+ through conductors 58 and 69, 5 lamp 1L and the contact members 1N5 and 1W3 to the supply conductor L_- . The lighting of the floor lantern at the lower floor for car 1 indicates to waiting passengers at the lower terminal that car 1 will be the next car to receive a dispatching 10 signal and start on an up trip. Therefore, the waiting passengers will move to and enter car 1.

Inasmuch as the floor lantern and the "next" lamp for car 1 are lighted, the timing motor 10 is rotating and the clutch 20 is energized and rotating the switch disc 24, the dispatching system operates next to give car 1 its "start" signal. The timed rotation of the disc 24 causes its contact member 30 to reach the point where it operates the switch arm 31 to temporarily separate the 20 contact members BT2 and close the contact members BT1. The temporary opening of the contact members BT2 interrupts the circuit for the bottom start signal relays. The temporary closing of the contact members BT1 energizes the 25 bottom signal storing relay BS by a circuit extending from the supply conductor L_+ through conductor 71, the contact members BT1, the coil BS, and conductor 61 to the supply conductor L_- .

The energized relay BS closes its contact members BS1 and BS2. The closing of the contact members BS1 completes a self-holding circuit for relay BS, extending from supply conductor L_+ through the contact members BS1, 1F2, 2F1, 3F1 and 4F1, the coil BS and conductor 61 to supply 35 conductor L_- .

As the timing motor 10 continues its operation, the cam 30 moves out of engagement with the switch arm 31, thereby permitting its biasing spring 31a to move the arm to open the contact 40 members BT1 and reclose the contact members BT2. Inasmuch as the contact members BS2 have been closed and the contact members BT2 are now reclosed, the start signal relay 1F for effecting the giving of the starting signal to car 1 45 is now energized by a circuit extending from the supply conductor L_+ through conductor 58, the contact members BT2 and BS2, conductor 72, the contact members 1N1 and 1W1, coil 1F, contact members 1G1 and selective resistor R2, to the 50 supply conductor L_- .

The energized relay 1F closes its contact members 1F1 and 1F5, and opens its contact members 1F2, 1F3 and 1F4. The closing of the contact members 1F1 completes a self-holding circuit 55 for the relay 1F. The opening of the contact members 1F2 deenergizes the storing relay BS, but the opening of its contact members BS2 has no effect upon the relay 1F, because of the self-holding circuit contact members 1F1. The opening of the contact members 1F3 deenergizes the dispatch preparing relay 1M of car 1 and restores it to its normal condition and ready for the next operation. The opening of the contact members 1F4 in the circuit of the coil of clutch 20 deenergizes that clutch, thereby stopping rotation of the disc 24 because it is not now connected to the timing motor shaft. The timing disc 24 will not start to operate for another dispatching interval until the bottom start signal relay 1F is 70 again deenergized.

The opening of the contact members 1M2 deenergizes the car selecting relay 1N, which opens its contact members 1N1, 1N2, 1N3, 1N4 and 1N5. The opening of the contact members 1N2 and 75

1N3 has no effect upon the system at this time, but the opening of the contact members 1N4 disconnects the start lamp 1C in car 1 from the supply circuit, and the opening of the contact members 5 1N5 opens the circuit of the lamp 1L of the floor lantern for car 1, so that the waiting passengers are not now directed to car 1 for the next up trip.

However, at the time the contact members 1N4 10 are opened in the circuit of the "next" lamp 1C in car 1, the closed contact members 1F5 of the start signal relay 1F complete a flickering circuit for the lamp 1C, which circuit extends from the supply conductor L+ through conductor 68, lamp 15 1C, the contact members 1F5, and the flicker device 45 and conductor 61 to supply conductor L-.

The lamp 1C is now in a flickering condition, and its flickering light is the starting or dispatching signal to the attendant in car 1 to start his car on the next up trip.

It will be assumed that the attendant on car 1 now starts his car away from the lower terminal and in so doing, operates a door-closing lever or starting switch (not shown) which effects the operation of the signal cancelling switch 1G to open its contact members 1G1 and 1G2. The opening of the contact members 1G1 deenergizes the bottom start signal relay 1F of car 30 1, thus causing that relay to open its contact members 1F5 to stop the flickering start signal of lamp 1C in car 1. The closing of the contact members 1F4 of the deenergized relay 1F restores the circuit for energizing the clutch 20, 35 and this causes the timing switch disc 24 to start rotating with the timing motor 10.

Inasmuch as we have seen how car 1 comes into the dispatching terminal or lower floor and gets its starting signal by reason of the attendant operating his up direction preparing button 1U and the operation of the timing mechanism, it will now be assumed that car 2 arrived before car 1 received its starting signal and left, and that the attendant in car 2 pushed his up direction preparing button 2U immediately upon his arrival at the lower floor. With this assumption we now have both cars 1 and 2 at the lower terminal, car 1 not yet having left but both cars have operated their preparing buttons 50 for conditioning the cars to receive the starting signal.

The arrival of the car 2 at the lower terminal automatically caused its down direction preference relay 2X to be deenergized and its up direction preference relay 2W to be energized to close its contact members 2W1, 2W2, and 2W3. The closing of the contact members 2W1 closed one gap in the circuit for the bottom start signal 2F of car 2. The closing of the contact members 2W2 closed a gap in the circuit for the car selecting relay 2N of car 2. The closing of the contact members 2W3 closed one gap in the circuit of the floor lantern 2L for car 2 at the lower floor.

65 The pressing of the button 2U energized the dispatch preparing relay 2M of car 2 by a circuit extending from the supply conductor L+, through the coil 2M, the contact members 2F3 and 2E2, the contact members of button 2U and conductor 61 to the supply conductor L-. The energized relay 2M closed its contact members 2M1 and 2M2, the closed contact members 2M1 closing a self-holding circuit. The closed contact members 2M2 closed one gap in the circuit 70 for the car selecting relay 2N, and it will be re-

called that the constantly operating sequence device K causes its contact members 2K to close and open rapidly. However, inasmuch as car 1 is at the lower floor and has its car selecting relay 1N energized, the closing of the contact members 2M2 and 2K do not cause relay 2N to pick up, because the selective resistor R3 prevents the flow of sufficient current to the coil of relay 2N when coil 1N is also being energized. Hence, it is seen that the operation of the selective resistor R3 in 10 conjunction with the car selecting relays 1N prevents the dispatching system from giving more than one starting or dispatching signal from the lower floor at one time.

Upon car 1 being given its flickering signal on 15 its lamp 1C by the energization of relay 1F and the deenergization of its car selecting relay 1N incident thereto, the car selecting relay 2N for car 2 becomes energized when sequence switch 2K closes by a circuit extending from supply 20 conductor L+ through resistor R3, conductor 74, the contact members 2W2, coil 2N and contact members 2M2 and 2K and conductor 61 to supply conductor L-. The relay 2N is sufficiently energized at this time because the coil of relay 25 1N no longer diverts part of the current passed through the resistor R3 and that resistor now passes sufficient current to energize relay 2M. Hence, it is seen that only one car will receive an up start signal at the lower floor at any one 30 time.

The energized relay 2N now closes its contact members 2N1, 2N2, 2N3, 2N4 and 2N5. The closing of the contact members 2N1 and 2N2 prepares for operation the circuits of the start signal relays 2E and 2F. The closing of the contact members 2N3 prepares a self-holding circuit for the relay 2N.

The closing of the contact members 2N4 lights the "next" car to start lamp 2C in car 2 by a circuit extending from the supply conductor L+ through conductor 75, lamp 2C, and contact members 2N4 and conductor 61 to the supply conductor L-. Hence, the "next" lamp 2C is 40 lighted in car 2 to inform the attendant therein 45 that his car is now scheduled to be the next car to receive the dispatching or start signal at the lower terminal.

The closing of the contact members 2N5 energizes the floor lantern 2L of car 2 at the lower 50 terminal by a circuit extending from the supply conductor L+ through conductor 58, lamp 2L and contact members 2N5 and 2W3 to the supply conductor L-. The operation of the lamp 2L now notifies the waiting passenger at the 55 lower floor that car 2 will be the next car to make an up trip.

Car 1 now leaves in response to its flickering signal, leaving car 2 at the floor. As stated before, when car 1 received its flickering signal 60 the timer disk 24 stopped rotation but when car 1 departed, it restarted disk 24 into rotation by the timing motor. Upon the expiration of the time necessary for the timing motor, operating at constant speed, to rotate the switch disk 24 65 from the position at which it was started by the response of the attendant on car 1 to his dispatching signal, to the point where the cam 30 again engages the switch arm 31, that arm again opens the switch BT2 and closes the switch BT1 70 temporarily. The opening of the switch BT2 interrupts the circuits of the start signal relay 2F and the closing of the contact members BT1 energizes the bottom signal storing relay BS as heretofore described in connection with car 1. 75

As the timer disk 24 continues rotation, the cam 30 moves away from the switch arm 31, permitting the biasing spring 31a to reclose the contact members BT2 thus causing the start signal 5 relay 2F for car 2 to be energized by a circuit extending from supply conductor L+ through conductor 58, the contact members BT2 and BS2, conductor 72, contact members 2N1 and 2W1, the coil 2F, the contact members 2G1 and the 10 selective resistor R2 to the supply conductor L-.

The energization of the relay 2F opens its contact members 2F1, 2F3 and 2F4 and closes its contact members 2F2 and 2F5. The opening of the contact members 2F1 deenergizes the storing relay BS. The closing of the contact members 2F2 completes a self-holding circuit for the relay 2F. The opening of the contact members 2F3 deenergizes the dispatch preparing relay 2M which in turn opens its contact members 2M2, 15 thereby deenergizing and restoring the car selecting relay 2N to its normal condition which in turn opens its contact members 2N4 to deenergize the next to start lamp 2C in car 2 and opens its contact members 2N5 to extinguish the floor 20 lantern 2L.

The opening of the contact members 2F4 deenergizes the clutch 20 and causes the switching disk 24 to be released from the timing motor 10 until such a time as it is reconnected thereto 30 by the attendant on car 2 responding to the dispatching signal after it is given.

The closing of the contact members 2F5 of the energized relay 2F connects the lamp 2C in car 2 through the flicker device 45 and now causes 35 the lamp 2C to receive a flickering or flashing circuit extending from the supply conductor L+ through conductors 75, lamp 2C, the contact members 2F5, conductor 76 and flicker device 45 and conductor 61 to the supply conductor L-. 40 Thereupon the attendant in car 2 is notified by the flickering lamp 2C to start his next up trip. As soon as the attendant on car 2 responds by operating some portion of the control system associated with the upward departure of the car 45 from the lower terminal, the switch 2G is deenergized to open its contact members 2G1 and 2G2. The opening of the contact members 2G1 deenergizes the bottom start signal 2F to open its contact members 2F5 thereby deenergizing 50 the dispatching signal in car 2 and closes its contact members 2F4 thereby energizing the clutch 20 and causing the starting switch disc 24 to begin another timing revolution.

By reason of the foregoing it will be seen that 55 when a car arrives at a terminal floor and the attendant thereon presses a direction preference button for connecting his car to the dispatching system, etc. the dispatching system will automatically give that car a dispatching or starting signal at a later period. It is also seen that the 60 interval between dispatching signals when cars are arriving at and leaving the floor in regular order will be equal to the time necessary for the timer motor to operate the timer switch one revolution plus the time it takes the attendant to respond to his starting signal after he receives it. Of course, the interval between starting signals will always vary slightly by reason of the 65 time the attendants take to respond to their starting signals. This variation is useful. It permits the system to automatically adjust itself to accommodate momentary heavy rushes of traffic and yet return to normal operation as soon as the traffic returns to normal.

70 For instance, when the traffic becomes heavy,

the cars will be crowded and the operators will be less quick to close the doors and leave the terminal. When the traffic is heavy, the larger number of passengers causes the attendant more difficulty in ascertaining whether or not it is safe 5 to start the car, and causes him more work in registering additional calls and answering inquiries. These and other conditions in connection with a crowded car cause delays not experienced with a few passengers. When traffic is 10 light and the operator has only a few people in his car, he will unconsciously respond quicker to the starting signal and the interval between starting signals will thereby automatically shorten. 15

When the cars are heavily loaded, the time necessary for a car to distribute the passengers among the upper floors must necessarily be greater than when traffic is light; hence under heavy traffic each car will necessarily require more time 20 in which to make its round trip. When my improved system is employed, the automatic increase in the intervals between the giving of starting signals automatically takes care of the increased time necessary for round trips of the 25 cars.

Of course, if an unlimited number of cars could be added when additional heavy traffic occurs, it would not be necessary to lengthen the starting intervals. However, in nearly all commercial systems the number of cars is limited and the best way known to handle heavy traffic is to lengthen the starting period so as to give the cars such time for their round trips as will enable each one to come in and receive his starting signal at the 35 natural time. Otherwise, the cars have a tendency to become bunched and to alternate in service at the intermediate floors. When they become bunched, three or four of the cars are liable to be absent from the starting station for a considerable period and then arrive there at practically the same time. This does not please the waiting passengers and hence it is found that my improved system of providing for automatically lengthening the starting interval when the traffic 40 becomes heavy, is very desirable.

As shown in the drawings, the signal lamps C in the cars may be operated when the cars are at the upper terminal to give the cars "next" signals and dispatching signals from that terminal in somewhat the same manner as the dispatching signals are given at the lower terminal. The top storing signal relay TS, the top start signal relays E, the down direction preparing buttons D and the down direction preference relays X, as well as the timer clutch 33 and the 55 timing switch arm 32 are provided for this purpose.

Assuming that no car is at the upper terminal but that car 1 is approaching that terminal at 60 the end of its up trip, the clutch 33 is energized as previously described and the switching disk 66 is rotating its cam member 78 toward the position where it will operate the switch arm 32 to open the contact members TT2 and close 65 the contact members TT1 for the purpose of giving the next starting signal. When car 1 arrives at the upper terminal, its up direction preference relay 1W is automatically deenergized and its down direction preference relay 1X is automatically energized by the operation of the control system (not shown) of the car.

The energization of the down direction preference relay 1X closes its contact members 1X1 and 1X2. The closing of the contact members 75

1X1 in the circuit of the top start signal relay 1E prepares that relay for operation under certain conditions. The closing of the contact members 1X2 connects the coil of relay 1N through selective resistor R3 to the supply conductor L+ and thereby prepares the relay 1N for operation.

Also upon the arrival of car 1 at the upper terminal it will be assumed that the attendant therein presses the down direction button 1D to connect the car with the dispatching system in addition to any other desired function.

The operation of the button 1D energizes the dispatch-preparing relay 1M of car 1 by a circuit extending from the supply conductor L+ through the coil 1M, the contact members 1F3 and 1E1, the contact members of button 1D and conductor 61 to the supply conductor L-. The energized relay 1M closes its contact members 1M1 and 1M2 to provide a self-holding circuit for itself and close one gap in the circuit of the car selecting relay 1N as previously described. Inasmuch as car 1 is at the upper terminal ready for its down trip and its direction preference relay X is energized, the contact members 1X2 in the circuit of the relay 1N are closed to assist in preparing that relay for energization. Also, as previously stated, the sequence device K is constantly opening and closing its switches and therefore the switch 1K closes its contact members soon after the relay 1N is prepared for operation, and then the relay 1N is energized by a circuit extending from the supply conductor L+ through the selective resistor R6, conductor 79, the contact members 1X2, coil 1N and the contact members 1M2 and 1K and conductor 61 to supply conductor L-. The energized relay 1N now closes its contact members 1N1, 1N2, 1N3, 1N4 and 1N5 as previously described.

The closing of the contact members 1N1 relates to the bottom start signal relay 1F and will not affect the upper terminal in any way. The closing of the contact members 1N2 closes one gap in the circuit of the top start signal relay 1E and prepares it for operation. The closing of the contact members 1N3 provides a self-holding circuit for the relay 1N.

The closing of the contact members 1N4 lights the start lamp 1C in car 1 to notify the attendant that his car will be the next to receive a down dispatching signal at the upper terminal, but the closing of the contact members 1N5 does not cause the lighting of the floor lantern 1L at the lower terminal because the up direction preference relay 1W of car 1 is not energized and its contact members 1W3 remain open. Hence, it is seen that the single signal lamp 1C in the car may be used for giving next-car-to-leave signals and dispatching signals in the car at either the lower terminal or the upper terminal.

Inasmuch as the clutch 33 is energized, the switching disk 66 is being rotated and its cam 78 now engages the switch arm 32 and moves the arm outwardly against the action of its biasing spring 32a, thereby opening the contact members TT2 and closing the contact members TT1. The opening of the contact members TT2 interrupts the circuit of the top start signal relay 1E for a short period to prevent the temporary completion of any undesired circuits therethrough. The closing of the contact members TT1 energizes the top signal storing relay TS by a circuit extending from the supply conductor L+ through conductor 81, the contact members TT1, the coil TS and conductor 61 to the supply conductor L-. The energized relay TS closes its contact mem-

bers TS1 and TS3 and opens its contact members TS2 and TS4. The closing of the contact members TS1 completes a self-holding circuit for the relay TS extending from the supply conductor L+ through the contact members TS1, 1E1, 2E1, 3E1 and 4E1 to the coil TS. The opening of the contact members TS2 and TS4 does not affect the operation of the upper dispatching signals under the present conditions. During the operation so far described the timing motor 10 has continued to operate the timing disc 66 and its cam 78 has now left the switch arm 32 and its biasing spring opens the contact members TT1 and recloses the contact members TT2. The opening of the contact members TT1 does not affect the relay TS because the relay has now established its self-holding circuit. However, the reclosing of the contact members TT2 in connection with the closed contact members TS3 of the energized relay TS energizes the top start signal relay 1E by a circuit extending from the supply conductor L+ through conductor 58, the contact members TT2 and TS3, conductor 82, the contact members 1N2 and 1X1, the coil 1E, the contact members 1G2 and the selective resistor R4 to the supply conductor L-.

The energization of the relay 1E opens its contact members 1E1, 1E2 and 1E4 and closes its contact members 1E3 and 1E5. The opening of the contact members 1E1 deenergizes the top signal storing relay TS and prevents that relay from maintaining the start signal in stored condition as it is now to be released to car 1. The opening of the contact members 1E2 deenergizes the dispatch preparing relay 1M of car 1 which in turn deenergizes the car selective relay 1N of car 1 which in turn opens its contact members 1N4 and thereby deenergizes the signal lamp 1C in car 1.

The closing of the contact members 1E3 provides a self-holding circuit for the relay 1E. The closing of the contact members 1E5 energizes the signal lamp 1C in car 1 by a circuit extending from the supply conductor L+ through the conductor 68, lamp 1C, contact members 1E5, flicker device 45 and conductor 61 to the supply conductor L-. Inasmuch as the lamp 1C is now connected through the flicker device 45, that lamp gives a flickering or flashing signal which serves as a dispatching signal to the attendant on car 1 to start his car to the lower terminal.

Inasmuch as the apparatus works rapidly there is practically no time interval between extinguishing the steady glow of lamp 1C as a-next-car-to-leave lamp and its flickering operation to give the dispatching signal. The opening of the contact members 1E4 deenergizes the clutch 33 and thereby stops rotation of the disk 66 by the timing motor. Hence the dispatching interval for the next car will not start until car 1 leaves the upper terminal.

Another advantage of this system is that one signal device or lamp serves, as shown, for receiving the "next" to start signal and the dispatching signal at both the lower terminal and the upper terminal, thereby effecting a saving in the number of signal devices.

It will be assumed now that the attendant on car 1 responds to the flickering dispatch signal by operating his car to leave the upper terminal and that this operation of the car control system (not shown) consequently operates the switch 1G of car 1 to temporarily open its contact members 1G1 and 1G2. The opening of the contact members 1G1 in the circuit of the start signal

relay 1F for the lower terminal has no effect. The temporary opening of the contact members 1G2 in the circuit of the top start signal relay 1E deenergizes that relay to close its contact members 1E1, 1E2 and 1E4 and open its contact members 1E3 and 1E5.

The closing of the contact members 1E2 again closes one gap in the circuit of the dispatch preparing relay 1M. The opening of the contact members 1E5 extinguishes the circuit through the lamp 1C, and thereby extinguishes the dispatching signal.

It may be noted in this connection that one advantage of this system is that the dispatching system continues operating the dispatching signal in a car until the attendant in that car responds to it, and that the dispatching signal of no other car can be operated until the dispatching signal in the car which should receive it is responded to. However the "next-car-to-leave" signal for some other car may be operated if that car is in condition to receive it.

The closing of the contact members 1E4 restores the clutch 33 to its energized condition and inasmuch as the timing motor 10 is running constantly, the timing disk 66 again picks up and starts its timing rotation to complete the timing interval for the next dispatching signal to be given to the next car.

30 No floor lanterns have been shown for the upper terminal, but, if desired, they may be provided and operated in the same manner as the floor lanterns 1L, etc. at the lower terminal.

It will be assumed now that car 2 arrives at 35 the upper terminal as car 1 leaves. It will also be assumed that the attendant on car 2 presses his down button 2D to prepare for a down trip and associate his car with the dispatching system. Upon arriving at the upper floor, the up 40 direction relay 2W for car 2 is automatically deenergized and its down direction preference relay 2X is automatically energized to close its contact members 2X1 and 2X2 for use in the down operation of car 2 in connection with the 45 control system (not shown). As shown in connection with the other cars, the pressing of the button 2D energizes the dispatch preparing relay 2M of car 2 which, in turn, energizes the car selecting relay 2N to operate the next start signal relay 2C on car 2 and prepare the top start signal relay 2E for energization when the timing motor 10 completes the interval rotation of the 50 timing disk 66. As the disk 66 completes its rotation, its cam member 78 operates the switch 55 arm 32 to open the contact members TT2 and close the contact members TT1 temporarily. The closing of the contact members TT1 energizes the top signal storing relay TS which, in turn, closes its contact members TS3 to energize the 60 top start signal relay 2E. As the timing motor continues its rotation, the contact members TT1 open and the contact members TT2 close, thereby energizing the top start signal relay 2E of car 2 to deenergize the relays M and N. This extinguishes the steady glow in the lamp 2C and causes that lamp to have a flickering light, thereby indicating to the attendant in that car that it is the next car to leave. As the attendant leaves, he operates the switch 2G to temporarily open 65 its contact members 2G1 and 2G2. The opening of the contact members 2G2 deenergizes the relay 2E, thus causing it to open its contact members 2E5 to extinguish the flickering lamp 2C and to close its contact members 2E4, thereby again 70 energizing the clutch 33 so that the timing motor 75

10 will again pick up and begin to operate the timing switch disk 66.

By reason of the foregoing, it will be seen that the cars will be dispatched at normal intervals of time from the lower terminal and from the upper 5 terminal as long as the attendants in the cars keep operating the preference buttons upon their arrival at the terminals.

At times, it may happen that the attendants close the doors and leave the upper terminal 10 quicker than they do at the bottom terminal and that in such cases the natural timing interval which comprises the amount of time it takes the car attendant to respond to a dispatching signal plus the amount of time it takes the timing motor to rotate the timing switch to a point where it opens its normally closed switch and temporarily closes its signal storing switch will be less than the equivalent timing periods at the lower terminal. That is, the car attendants 15 may start quicker at the upper terminal than they do at the lower terminal after receiving their starting signals. The dispatching system may also drift into such an operation by reason of the number of passengers being served or the 20 number of floors being served in a particular direction. Such a condition does not tend toward the best operation of the system and in order to overcome difficulties of this nature, I have provided a means which will automatically 25 adjust the operation of the terminal signals with respect to the bottom terminal signals.

For instance, inasmuch as the clutches for the top and bottom signals are independent, a given operator may respond at normal speed at the 35 top terminal and slow speed at the bottom terminal. This will have the effect of dispatching the cars faster from the top terminal than at the bottom. This will continue until the cars begin coming in late for their signal at the top 40 terminal. When a car is late, the signal will be stored by the relay TS for the upper terminal, as no top start relay E can be energized until a car is present at the terminal and is prepared for a down trip.

In order to prevent a continued dispatching of the cars faster at the top terminal than at the bottom terminal, I have provided a top signal delay relay TSA and have so connected it that it will lengthen the timing interval for the top 50 dispatching signals when the cars begin to arrive late for their signals.

The time delay relay operates as follows: Assume that after the departure of car 2 no car is at the top terminal when the timing system 55 is ready to give a dispatching signal at that terminal. Under these conditions, the operation of the timing motor temporarily opens the switch TT2 and closes the timing switch TT1. The closing of switch TT1 energizes the top storing signal relay TS by the circuit previously described. The energized relay TS closes its contact members TS1 and TS3 and opens its contact members TS2 and TS4. The closing of contact members TS1 completes a self-holding circuit for relay TS 60 and the closing of the contact members TS3 prepares a circuit for energizing the start signal relay of the next car ready to leave the upper terminal. Inasmuch as no car is at the upper terminal, the start signal is not given at this 65 time but is stored for the next car. This storing action is effected because the contact members TS3 of the energized storing relay TS remain closed along with the normally closed contact members TT2 in the circuits of the start signal 70 75

relays E for all of the cars. The contact members TS3 will remain closed until some car arrives and energizes a relay E to open the self-holding circuit of relay TS.

5 At the same time, the normally closed contact members TS2 are opened in the circuit of the time delay relay TSA, thereby deenergizing that relay. The relay TSA has included in its circuit a resistor R1 and is so designed that it will delay 10 closing its contact members for a predetermined time after it is deenergized. This time is that produced by the stored energy of the coil discharging through the resistor until the current in the coil falls low enough to permit the contacts of the relay to open. Therefore, when relay TS is energized and immediately opens its contact members TS4 and the contact members 15 TS1 of the deenergized relay TSA still remain open, because of their time delay, the circuit 20 for the electromagnetic clutch 33 is opened, thereby deenergizing that clutch to stop the rotation of the timing disk 66.

The deenergized time delay relay TSA fails to close its contact members TS1 for a predetermined time after the energized relay TS opens its contact members TS4. Hence, the circuit for clutch 33 remains open for a predetermined time and for this predetermined length of time the switch disk 66 remains unrotated. When the predetermined time delay for the relay TSA expires, its contact members TS1 close, thus again energizing the electromagnetic clutch 33 to cause the timing motor T to again pick up the timing disk 66 and start rotating it toward its position 35 for operating the switch arm 32. Hence the timing interval has been lengthened by the time it took the time delay relay to close its contact members.

It should be noted here that the contact members TS1 in the circuit of the clutch 33 are held open at all times, except when a signal is stored by the storing relay TS, and that during regular operation of the system with the cars on time, the energization of the clutch 33 is controlled by the 40 contact members TS4 of relay TS and by the contact members of the starting signal relays E, and that the lengthening of the dispatching interval is effected by the simultaneous opening of the contact members TS4 and TS1 for a predetermined length of time when no cars are at the upper terminal.

Assume that car 3 now arrives late at the upper terminal after the timing disk 66 resumes its rotation and that the attendant thereon presses the button 3D for the down direction, and that the preference relay 4X is energized. The car 3 is now prepared to receive the down dispatching signal. Inasmuch as the dispatching signal has been stored by the relay TS remaining energized, 55 the pressing of the button 3D in car 3 energizes the relay 3M, which, in turn, energizes the relay 3N, which, in turn, energizes the relay 3E, as described in connection with the other cars.

The energized relay 3E opens its contact members 60 3E1, 3E2 and 3E4 and closes its contact members 3E3 and 3E5. The closed contact members 3E3 complete a self-holding circuit for relay 3E. The open contact members 3E1 deenergize the signal storing relay TS. The open contact 65 members 3E2 deenergize the relay 3M which, in turn, deenergizes the relay 3N. The open contact members 3E4 deenergize the clutch 33, thereby stopping rotation of the timing disk 66 until car 3 departs, thus causing another period of delay in the dispatching interval. The closed con-

tact members 3E5 complete the circuit for the dispatching lamp 3C in car 3 through the flicker device 45, thereby causing that lamp to give the stored up dispatching signal to car 3. The attendant in car 3 now operates its control system to start on the down trip and in so doing opens the switch contact members 3G2. This deenergizes the dispatching signal relay 3E which extinguishes the dispatching signal and closes its contact members 3E4, thereby again energizing the clutch 33 to cause the timing disk 66 to resume its rotation to measure the dispatching interval.

After car 3 leaves and cancels its starting signal, it will be assumed that car 4 arrives on time 15 at the upper terminal and that the attendant therein operates its down button 3D and the up preference relay 4W is deenergized and the down preference relay 4X is energized to prepare that 20 car for its down trip.

In the meanwhile, the timing motor 10 has been rotating the disk 66 to measure the dispatching interval. It will be assumed that the disk 66 completes its timing rotation and temporarily opens the contact members TT2 and closes the 25 contact members TT1. The closing of the contact members TT1 energizes the signal storing relay TS as has been described, which closes its contact members TS3 in the circuit of the starting signal relay 4E. As the disk 66 continues its rotation, it opens the contact members TT1 and closes the contact members TT2, thereby energizing the starting signal relay 4E to give the dispatching signal to car 4 as described in connection with the other cars. After car 4 receives 30 the dispatching signal on its lamp 4C, the attendant operates its control system for the down trip, thereby energizing the switch 4G to open its contact members 4G2, thus deenergizing the relay 4E which closes its contact members 4E4, 40 thereby, in turn, energizing the clutch 33 to again start the disk 66 upon another timing rotation.

In reviewing the operation of the dispatcher in connection with cars 2, 3 and 4 at the upper 45 terminal, it is seen that the timing disk 66 was stopped during the time it took car 2 to respond to its dispatching signal; that the disk then started and rotated until the dispatching interval was completed for giving a dispatching signal 50 to the next car (which signal was stored); that the timing disk, after effecting the storing of the signal, stopped rotation until the deenergized time delay relay TSA closed its contact members; that the timing disk then started rotation to 55 measure another dispatching interval but was stopped during such rotation by the late arrival of car 3 and was again started by the departure of car 3; that the timing disk then completed its rotation and again operated its switch arm 32 to 60 effect the giving of a dispatching signal to car 4, which had arrived on time. By this it is seen that the dispatching interval between the giving of the signal to car 2 and the storing of the signal for car 3 consisted of the time it took the attendant on car 2 to respond to his dispatching signal plus the time it took the timing disk to rotate to the point for giving another dispatching signal. It is also seen that the dispatching interval between the time when the relay TS 65 stored the dispatching signal for the next car (car 3) and the time when the dispatching signal was given to car 4 consisted of three periods instead of two; that is, the first period was the time consumed by the time delay relay TSA in 70 75

closing its contact members; the second period was the time the disk 66 took to make its measuring rotation; and the third period was the time it took the operator on car 3 to respond to the 5 stored dispatching signal. Hence, it is seen that when the cars arrive late at the upper terminal the dispatching intervals are lengthened by the time it takes the time delay relay to close its contact members after being deenergized by the 10 storing of a dispatching signal.

Inasmuch as the delay caused by the deenergization of the time delay relay TSA will occur whenever the cars fail to arrive at the upper terminal within a dispatching interval, it will 15 be readily seen that the system will provide for automatically adjusting the top terminal dispatching signals with respect to the bottom terminal dispatching signals and that the system will not require manual attention or operation 20 for controlling itself in this respect.

Although I have illustrated and described only one specific embodiment of my invention, it is to be understood that many modifications thereof and changes therein may be made without departing from the spirit and scope of the 25 invention.

I claim as my invention:

1. In a dispatching system for a plurality of cars operating from a dispatching terminal, a 30 continuously operating timing motor, a timing switch, a signal device for each of said cars, and control means for individually rendering each of said signal devices subject to control by said timing switch, said control means including clutch 35 means for connecting the timing switch to the timing motor to effect delayed operation of the timing switch, sequence means operated by said timing motor for selecting the next car to receive a signal, and individual means for each 40 car operable when the corresponding car is in a region adjacent said dispatching terminal for rendering the sequence means effective to select the corresponding car.

2. In a dispatching system for a plurality of 45 cars operating from a dispatching terminal, a continuously operating timing motor, a sequence device operated by the timing motor, a timing switch, means for connecting the timing switch to the timing motor to effect operation of the 50 switch at predetermined intervals, a plurality of signal devices, one for each car, a manual operated means for each car, means responsive to operation of the manual means on a car, operation of the switch and operation of the sequence 55 device for operating the signal device of a car to give it a dispatching signal and for operating the connecting means to disconnect the switch from the motor.

3. In a dispatching system for a plurality of 60 cars operating from a dispatching terminal, a continuously operating timing motor, a sequence device operated by the timing motor, a timing switch, means for connecting the timing switch to the timing motor to effect operation of the 65 switch at predetermined intervals, a plurality of signal devices, one for each car, a manual operated means for each car, means responsive to operation of the manual means on a car, operation of the switch and operation of the sequence 70 device for operating the signal device of a car to give it a dispatching signal and for operating the connecting means to disconnect the switch from the motor, means responsive to response of that car to that dispatching signal for operating the connecting means to reconnect the

switch to the motor for operation over another interval.

4. In a dispatching system for a plurality of cars operating from a dispatching terminal, a continuously operating timing motor, a sequence device operated by the timing motor, a timing switch, means for connecting the timing switch to the timing motor to effect operation of the switch at predetermined intervals, a plurality of signal devices, one for each car, a manual operated means for each car, a car selecting means for each car responsive to operation of the manual means for that car and to operation of the sequence device for selecting the car to receive the next dispatching signal, and means responsive to operation of the selecting means and operation of the timing switch for operating the signal device in the selected car to give it a dispatching signal.

5. In a dispatching system for a plurality of 20 cars operating from a dispatching terminal, a continuously operating timing motor, a sequence device operated by the timing motor, a timing switch, means for connecting the timing switch to the timing motor to effect operation of the 25 switch at predetermined intervals, a plurality of signal devices, one for each car, means responsive to manual operation for each car, a car selecting means for each car responsive to operation of the manual means for that car and to operation of the sequence device for selecting the car to receive the next dispatching signal, means responsive to operation of the selecting means and operation of the timing switch for operating the signal device in the selected car to 30 give it a dispatching signal and for operating the connecting means to disconnect the timing switch from the timing motor, means responsive to that car responding to its dispatching signal for operating the connecting means to reconnect the switch for operation by the timing motor over another interval, and means responsive to no manual operated means being operated at the end of the timing interval of the timing switch for storing the dispatching signal until the 40 manual means of some car is operated.

6. In a dispatching system for a car operating from a dispatching terminal, a continuously operating timing motor, a timing switch, a sequence device operated by the timing motor, 50 means for connecting the timing switch to the timing motor to effect operation of the timing switch at predetermined intervals, a signal device for the car, a manual operated means for the car, means responsive to the operation of the 55 manual means of the car, operation of the timing switch and operation of the sequence device for operating the signal device on the car to give it a dispatching signal, and means responsive to the failure of operation of the manual means 60 and to operation of the timing switch for storing the dispatching signal.

7. In a dispatching system for a plurality of cars operating from a dispatching terminal, a continuously operating timing motor, a sequence 65 device operated by the timing motor, a timing switch, means for connecting the timing switch to the timing motor to effect operation of the switch at predetermined intervals, a plurality of signal devices, one for each car, a manual operated means for each car, a car selecting means for each car responsive to operation of the manual means for that car and to operation of the sequence device for selecting the car to receive the next dispatching signal, and means responsive 70 to operation of the timing switch for storing the dispatching signal.

sive to operation of the selecting means for rendering the signal device of that car effective to indicate that it will be the next car to leave.

8. In a dispatching system for a plurality of cars operating from a dispatching terminal, a continuously operating timing motor, a sequence device operated by the timing motor, a timing switch, means for connecting the timing switch to the timing motor to effect operation of the switch at predetermined intervals, a plurality of signal lamps, one for each car, a manual operated means for each car, a car selecting means for each car responsive to operation of the manual means for that car and to operation of the sequence device for selecting the car to receive the next dispatching signal, means responsive to operation of the selecting means for lighting the signal lamp of that car to indicate that it will be the next car to leave, a flicker device, and means responsive to operation of the selecting means and the timing switch for extinguishing the signal lamp and relighting it through the flicker device to give that car its dispatching signal.

25 9. In a dispatching system for a plurality of cars operating from a dispatching terminal, a continuously operating timing motor, a sequence device operated by the timing motor, a timing switch, means for connecting the timing switch to the timing motor to effect operation of the switch at predetermined intervals, a plurality of signal devices, one for each car, a plurality of floor lanterns, one for each car, a manual operated means for each car, a car selecting means for each car responsive to operation of the manual means for that car and to operation of the sequence device for selecting the car to receive the next dispatching signal, and means responsive to operation of the selecting means for operating the floor lantern of that car to indicate to waiting passengers that it will be the next car to leave.

10. In a dispatching system for a plurality of cars operating from a dispatching terminal, a continuously operating timing motor, a sequence device operated by the timing motor, a timing switch, means for connecting the timing switch to the timing motor to effect operation of the switch at predetermined intervals, a plurality of signal devices, one for each car, a plurality of floor lanterns, one for each car, a manual operated means for each car, a car selecting means for each car responsive to operation of the manual means for that car and to operation of the sequence device for selecting the car to receive the next dispatching signal, means responsive to operation of the selecting means for operating the floor lantern of that car to indicate to waiting passengers that it will be the next car to leave, and means responsive to operation of the selecting means and the timing switch for extinguishing the floor lantern and operating the signal device of that car to give it a dispatching signal.

65 11. In a dispatching system for a car operated from a dispatching terminal, a continuously operating timing motor, a timing switch, a sequence device operated by the timing motor, means for connecting the timing switch to a timing motor to effect operation of the timing switch at predetermined intervals, a signal device for the car, a manual operated means for the car, means responsive to the operation of the manual means on the car, operation of the timing switch and operation of the sequence de-

vice for operating the signal device on the car to give it a dispatching signal, and means responsive to a manual means not being operated when the timing switch completes an interval for disconnecting the timing switch from the timing motor for a predetermined interval.

5 12. In a dispatching system for operating a plurality of cars from a dispatching terminal, a timing means, means responsive to operation of the timing means for giving dispatching impulses at predetermined intervals and means responsive to the failure of any car to be conditioned to receive a dispatching impulse for delaying operation of the timing means for a predetermined interval and then starting the timing means over another interval of operation.

10 13. In a dispatching system for a plurality of cars operating between an upper terminal and a lower terminal, a signal device for each car, a constantly operating timing motor, a timing mechanism, means responsive to operation of the timing mechanism for giving dispatching impulses at predetermined intervals for operating the signal devices to give dispatching signals to the cars, means associated with the lower terminal and with the upper terminal for storing the dispatching impulses when no cars are conditioned to receive dispatching signals, and means associated with the upper terminal for delaying the operation of the timing mechanism for a predetermined interval when no car is conditioned to receive a dispatching signal at the upper terminal, whereby the late arrival and conditioning of the cars for signals at the upper terminal will automatically adjust the relative time 35 of the giving of signals at the upper terminal with respect to the lower terminal.

25 14. In a dispatching system for a plurality of cars operating between an upper terminal and a lower terminal, a signal device for each car, a constantly operating timing motor, a timing mechanism operated by the motor, means responsive to operation of the timing mechanism for giving dispatching impulses at predetermined intervals for operating the signal devices to give dispatching signals to the cars, and means associated with the upper terminal for delaying the operation of the timing mechanism for a predetermined interval when no car is conditioned to receive a dispatching signal at the upper terminal, whereby the late arrival and conditioning of the cars for signals at the upper terminal will automatically adjust the relative time of the giving of signals at the upper terminal with respect to the lower terminal.

40 15. In a dispatching system for a plurality of cars operating from a dispatching terminal, a timing device, a sequence device, a plurality of start signal devices, one for each car, a start signal means, a manually-operated means associated with each car for preparing it to receive a dispatching signal, a preference means associated with each car for controlling its direction of operation, a selecting means associated with each car and responsive to operation of the preparing means, the direction preference means and the sequence device for selecting the next car to receive a dispatching signal, means responsive to unoperated condition of the start signal means for connecting the timing switch for operation by the timing device after a predetermined interval, and means responsive to operation of the timing device, the car selecting means and the direction preference means for causing operation of the signal device of the car corresponding 75

to the operated selecting means to give that car a dispatching signal.

16. In a dispatching system for a plurality of cars operating from a dispatching terminal, a timing device, a sequence device, a plurality of start signal devices, one for each car, a manually operated means associated with each car for preparing it to receive a dispatching signal, a preference means associated with each car for controlling

its direction of operation, a selecting means associated with each car and responsive to operation of the preparing means, the direction preference means and the sequence device for selecting the next car to receive a dispatching signal,

15 means for preventing the selecting means from selecting more than one car at one time to receive the dispatching signal, and means responsive to operation of the timing device, the car selecting means and the direction preference means for

20 causing operation of the signal device of the car corresponding to the operated selecting means to give it a dispatching signal.

17. In a system for dispatching a plurality of cars from a dispatching station, a plurality of

25 signal devices, one for each car, a timing means, means for causing the timing means to operate at selected intervals, means responsive to operation of the timing means for an interval for giving a dispatching impulse to the signal device of a car

30 to give it a dispatching signal, means responsive to the failure of a car to be conditioned to receive a dispatching signal for storing the dispatching impulse until a car is conditioned to receive it and for delaying the restarting of the timing means

35 for a predetermined interval during the storing of the dispatching impulse.

18. In a dispatching system for a plurality of cars operating from a dispatching station, a plurality of signal devices, one for each car, a timing

40 means, means responsive to operation of the timing means over a predetermined interval for giving a dispatching impulse to the signal device of a car to give it a dispatching signal, and means responsive to the failure of a car to be conditioned

45 to receive the dispatching signal for delaying the operation of the timing means for a predetermined period.

19. In a dispatching system for a plurality of cars operating from a dispatching station, a

50 plurality of signal devices, one for each car, a timing means, means responsive to operation of the timing means over a predetermined interval for giving a dispatching impulse to the signal device of a car to give it a dispatching signal,

55 and means responsive to the failure of a car to be conditioned to receive the dispatching signal for storing the dispatching impulse and for delaying the operation of the timing means for a predetermined period.

60 20. In a dispatching system for dispatching a plurality of elevator cars from each of two floors; a dispatching device in each of said cars; a timing device for giving a start signal to a car at one floor and to another car at the other

65 floor a predetermined time later, and means responsive to the operation of said cars for changing said predetermined time for a subsequent pair of cars.

21. In a dispatching system for a plurality of

70 cars operating from a dispatching station, a plurality of signal devices, one for each car, a timing means, means responsive to operation of the timing means for a predetermined interval for operating the signal device of one of the cars to

75 give a dispatching signal to that car and stop the

timing means, and means responsive to that car answering that dispatching signal for effecting operation of the timing means for another predetermined interval, whereby the normal interval between consecutive dispatching signals comprises the time it takes the attendant on a car to answer a dispatching system plus the time it takes the timing means to operate over its predetermined interval.

22. In a dispatching system for a plurality of 10 cars operating from a dispatching station, a plurality of signal devices, one for each car, a timing means, means responsive to operation of the timing means for a predetermined interval for operating the signal device of one of the cars to 15 give a dispatching signal to that car and stop the timing means, means responsive to that car answering that dispatching signal for effecting operation of the timing means for another predetermined interval, whereby the normal dispatch- 20 ing interval between consecutive dispatching signals comprises the time it takes the attendant on a car to answer a dispatching system plus the time it takes the timing means to operate over its predetermined interval, means responsive to no car being conditioned to receive a dispatching signal for storing that dispatching signal until a car is ready to receive it, and means responsive to no car being conditioned to receive a dispatching signal for delaying the operation 30 of the timing means for an interval.

23. In a dispatching system for a plurality of cars operating from a dispatching station, a plurality of signal devices, one for each car, a timing means, means responsive to operation of the timing means for a predetermined interval for operating the signal device of one of the cars to give a dispatching signal to that car and stop the timing means, means responsive to that car answering that dispatching signal for effect- 40 ing operation of the timing means for another predetermined interval, means responsive to no car being ready to receive a dispatching signal for storing that dispatching signal until a car is ready to receive it, and means responsive to no car being ready to receive a dispatching signal for delaying the operation of the timing means for a predetermined interval, whereby the interval between dispatching signals when a car arrives late at the station comprises the time it takes an attendant to answer a signal plus the time of delayed operation of the timing means plus the time it takes the timing means to operate over its predetermined interval.

24. In a system for dispatching a car from 55 an upper dispatching floor and from a lower dispatching floor, a single signal device in the car, a timing motor, and means associated with the timing motor and operated thereby for operating that signal device when the car is at the lower floor to give a "next car to leave" signal and later give a dispatching signal and for operating it at the upper floor to first give a "next car to leave" signal and later give a dispatching signal at that floor.

25. In a dispatching system for a group of elevators, means for giving dispatch signals from each of two floors including a timing device for operating said signal means at intervals, a single signal device in each of said cars, and means responsive to said timing device and the operation of said cars for causing one of said signal devices to give preparatory signals and start signals on the associated car at either of said dispatching floors.

26. In a dispatching system for a plurality of cars operating between an upper terminal and a lower terminal, a plurality of signal devices, one for each car, a plurality of start signal relays associated with the lower terminal, a plurality of start signal relays associated with the upper terminal, a timing motor, a timing switch for effecting operation of the signal devices at the lower terminal, a timing switch for effecting operation of the signal devices at the upper terminal, means responsive to inactive condition of the start signal relays associated with the lower terminal for connecting the timing switch associated with the lower terminal to the timing motor for operation thereby, and means responsive to inactive condition of the start signal relays associated with the upper terminal for connecting the timing switch associated with the upper terminal to the timing motor for operation thereby.

27. In a timing device for an elevator dispatcher, the combination with contacts for giving a dispatch signal to any of a group of elevators, of a motor, means operated by said motor for closing said contacts at intervals, and means for rendering said first-named means ineffective to operate said contacts thus to lengthen the time interval between two successive closings of the contacts, said last-named means being responsive to a function of starting one of the cars for rendering effective the first-named means to reoperate said contacts.

28. In a dispatching system for an elevator car operating in an upward and downward cycle of movement between an upper dispatching terminal and a lower dispatching terminal, signalling means including timing means for initiating start signals for said car with time delay, means effective at predetermined points in said upward and downward cycle of movement for controlling said timing means to effect delayed initiation of start signals when said car is standing at said upper terminal and when said car is standing at said lower terminal, and means effective during an unbalanced directional condition of traffic carried by said car for modifying the operation of said signalling means to change the relative magnitudes of time delay at said upper and lower dispatching terminals so as to improve the service of said car for said unbalanced directional condition.

29. In a dispatching system for a bank of elevator cars each operating in an upward and downward cycle of movement between an upper dispatching terminal and a lower dispatching terminal, signalling means including individual start signal means for each of said cars and timing means for initiating operation of said start signal means with time delay, means effective at predetermined points in the upward and downward cycle of movement of each of said cars for controlling said timing means to effect delayed initiation of start signals for the corresponding car when the corresponding car is standing at said upper terminal and when the corresponding car is standing at said lower terminal, and means effective during an unbalanced directional condition of traffic carried by said bank for modifying the operation of said signalling means to change the relative magnitudes of time delay at said upper and lower dispatching

terminals so as to improve the service of said bank for said unbalanced directional condition.

30. In a dispatching system for a bank of elevator cars each operating in an upward and downward cycle of movement between an upper dispatching terminal and a lower dispatching terminal, signalling means including individual start signal means for each of said cars and timing means for initiating operation of said start signal means with time delay, means effective at predetermined points in the upward and downward cycle of movement of each of said cars for controlling said timing means to effect delayed initiation of start signals for the corresponding car when the corresponding car is standing at said upper terminal and when the corresponding car is standing at said lower terminal, and means effective when the traffic carried by said bank is predominately downward for modifying the operation of said signalling means to increase the relative time delay at said upper dispatching terminal as compared with the time delay provided by said timing device for cars at said lower dispatching terminal.

31. In a dispatching system for a bank of elevator cars operating between an upper dispatching terminal and a lower dispatching terminal, signalling means including individual start signal means for each of said cars and a common timing means for initiating operation of said start signal means with time delay, control means for individually rendering each of said start signal means subject to control by said timing means, said control means including sequence means for selecting the next car to receive a start signal and including individual means for each car operable when the corresponding car is in a region adjacent one of said dispatching terminals for rendering the sequence means effective to select the corresponding car, and means responsive to a predetermined condition of traffic carried by said bank for modifying the operation of said signalling means to change the total time delay provided thereby for each car at said upper and lower dispatching terminals so as to improve the service of said bank for said predetermined condition of traffic.

32. In a dispatching system for a bank of elevator cars operating between an upper dispatching terminal and a lower dispatching terminal, signalling means including individual start signal means for each of said cars and a common timing means for initiating operation of said start signal means with time delay, control means for individually rendering each of said start signal means subject to control by said timing means, said control means including sequence means for selecting the next car to receive a start signal and including individual means for each car operable when the corresponding car is in a region adjacent one of said dispatching terminals for rendering the sequence means effective to select the corresponding car, and means effective when the traffic carried by said bank is predominately downward for modifying the operation of said signalling means to increase the relative time delay at said upper dispatching terminal as compared with the time delay provided by said timing device for cars at said lower dispatching terminal.
